UNITED STATES PATENT OFFICE.

FITZHUGH TOWNSEND, OF NEW YORK, N. Y., ASSIGNOR TO GENERAL RAILWAY SIGNAL COMPANY, A CORPORATION OF NEW YORK.

SYSTEM OF AUTOMATIC BLOCK-SIGNALING FOR ELECTRIC RAILWAYS.

1,129,143.

Specification of Letters Patent. Patented Feb. 23, 1915.

Original application filed June 16, 1904, Serial No. 212,798. Divided and this application filed April 27, 1905. Serial No. 257,572.

To all whom it may concern:

Be it known that I, FITZHUGH TOWNSEND, a citizen of the United States, residing at New York city, county of New York, State of New York, have invented a System of Automatic Block-Signaling for Electric Railways, of which the following is a specification.

My invention relates to a system where the operation of the signals is controlled by the motion of a motor vehicle into and out of a block and while in the block. In the practical operations of such a system, several requirements must be fulfilled in order that the normal conditions of operation of the railway shall not be interfered with, *i. e.*, the traffic rails must be segregated into block sections, the power current which operates the motor vehicle must flow along the traffic rails from one block section to the next without being impeded, the traffic rails should have an equal conductivity and both serve as return conductors for the power current, and means provided to increase the conductivity of the return circuit when desired, by what is technically known as "return" or "negative feeders".

Systems of automatic block signaling have heretofore been proposed which, in a measure, complied with one or more of the above stated requirements. In one of such systems, the traffic rails have been divided into block sections by means of insulating joints, and in order to facilitate the return of the power current, such joints have been bridged by reactance coils. Such system, however, does not give a complete use of the divided rail as a conductor for the power current. Where such system is supplied by a direct power current, the reactance coils interposed between the ends of the sections of the divided rail materially increase the ohmic resistance of the divided rail relative to that of the continuous rail, with the result, that the major portion of the power current is diverted to the continuous rail. Consequently, instead of having two rails of equal resistance, as a return for the power current as in ordinary railways, the conductivity of the two rails, divided and continuous, is equal only to approxi-

mately that of one rail and a fraction. Where such a system is supplied by an alternating power current, the disadvantage mentioned is found to be greatly increased, by the fact that the reactance coils oppose a counter-electro-motive force of self-induction, as well as ohmic resistance to the power current, with the result that the current carried by the divided rail is still further diminished relative to that carried by the continuous rail.

In the system which I have designed, both traffic rails are divided into block sections by insulation interposed between the ends of the rails. In order to allow the power current to return along the traffic rails and pass from one block section to the next, I interpose what I term "bonding-coils" between the rails at the points of division between the blocks and in such manner that the power current flows through each bonding coil (in at both ends and out at the middle point of the coil) in such manner as to produce no magnetization of the core on which the coil is wound. The advantage secured by the arrangement of the bonding-coils as employed by me, are: Owing to the small amount of iron and copper required to form the bond, such bonds are cheap in construction. The drop in volts due to the passage of the power current through the bonding-coils is greatly diminished. In the case of an alternating current railway, (where the power current produces no magnetization in the bonding-coils at any time), no counter-electro-motive force of self-induction will impede the power current in its passage along the traffic rails from one block section to the next.

My improved system is applicable to roads operated either by direct or alternating current.

In order to control the signaling devices, an alternating current is employed, (irrespective of whether the power current is a direct or an alternating current), which is preferably fed into each block section at the end of the block at which the car normally leaves the block; (this current I shall denote in this specification as the "signaling current.") The signaling current produces a

difference of potential between the traffic rails, which difference of potential is adapted to normally, that is, when a block is not occupied by a motor vehicle, energize a relay device connected across the traffic rails, preferably at the end of the block section at which the car normally enters the block. This relay device normally acts to close a local circuit in such a way that the signaling device employed will indicate a clear signal. The presence of a motor vehicle in a block section, through the wheels and axles of the car, or any suitable contact device, serves to short circuit the relay device; or in other words, shunt the difference of potential around the relay device, thus deenergizing the relay and causing the signaling device to indicate a danger signal. The relay employed may be of any definite type. I prefer, however, to use a relay which will be selective in character, and such as will only be actuated by an electromotive force across the rails, having the particular frequency of the signaling current employed. I have described in this specification a particular form of relay. I, however, make no claim in this application for such relay.

The signaling current employed may be derived from any suitable source. In the drawings I have shown three different methods of obtaining signaling current; that is, the signaling current may be obtained from an independent generator, Figures 1 and 4, from the generator which furnishes the power current, (the power current being of one phase and the signaling current of another phase), Fig. 2, and from the same generator which furnishes the power current but as a segregated current, Fig. 3.

The accompanying drawings will serve to illustrate my invention, in which—

Fig. 1 is a diagram illustrating my improved system as applied to an alternating current railway, with two generators, one for the power current, and one for the signaling current. Fig. 2 shows my system as applied to an alternating current railway, with a single generator employing one phase for the power current and one phase for the signaling current. Fig. 3 shows my system as applied to an alternating current railway with a single generator, with the signaling current segregated from the power current. Fig. 4 shows my system as applied to a direct current railway, with a direct current generator for the power current and an alternating generator for the signaling current.

Referring to the drawings: A indicates the generator for the power current. In Figs. 1 and 3, this generator is an alternating current generator of the single phase type; in Fig. 2, an alternative current generator of the two phase type, and in Fig. 4

a direct current generator. I wish it understood that the power current may be derived from any suitable source of electricity, as is the case with ordinary electric railways, that is, the power current may be an alternating current of single phase or polyphase, a direct current, or a pulsating current.

B, Figs. 1 and 4, indicates the generator for the signaling current. In Figs. 2 and 3, the signaling current is derived from the generator A, which furnishes the power current. In Fig. 2, the signaling current is taken off from a different set of collector rings of the generator A from that of the power current and differs in phase from the power current, and which current is used to excite the primary 5 of a transformer C. In Fig. 3, the signaling current is a segregated current from the power current delivered from generator A, as will be described.

6 indicates the outgoing feeder contact conductor; D motor vehicle; 7, traveling contact; 8, 9, traffic rails. The traffic rails are shown as divided into three blocks or sections X, Y, Z; the corresponding rails of respective sections being insulated from each other or otherwise separated. The feeder contact conductor 6 and the rails 8, 9 are connected to the terminals of the power generator A and form a power circuit.

In order to connect the traffic rails 8, 9 of the blocks X, Y, Z, together, and thus furnish two return paths for the power current to the generator A, and which paths shall be of equal resistance, I make use of the bond E, which consists of an iron core 10, on which is wound a coil of copper wire 11, which coil is connected across the rails 8, 9, at the left hand end of each block. Also the bond transformer F, which consists of the core 12, on which is wound the copper wire coils 13, 14. The coil 13 is connected, like the coil 11, across the traffic rails 8, 9, but at the opposite end of each block. The coil 14 is connected, one end to the center of the coil 13, and the other end to a conductor 15. A feeder conductor 15 is connected at one end to the source of the signaling current, that is, in Figs. 1 and 4, to one terminal of the generator B; in Fig. 2, to one terminal of the secondary 16 of transformer C; in Fig. 3 a feeder contact conductor 6 takes the place of the conductor 15. The coil 14 forms the primary coil of the bond transformer F, and as it is connected across the terminals of the signaling current, serves to excite the coil 13, which coil serves a double purpose, *i.e.*, that of a bond and that of the secondary of transformer F. The current from each coil delivered to the traffic rails 8, 9, creates a difference of potential between these traffic rails, which current is used, as will hereafter be described, to operate a relay when a motor car is not in a block, but

which current is short-circuited when a motor car moves into a block. The coils 11, 13 of bond E and bond transformer F, are connected together at their middle point, by 5 means of a conductor 17.

The operation of the bond E and bond transformer F, so far as relates to their function as a bond, will now be understood. The power current from a rail 8 flows 10 through the left hand half of the coil 11 to conductor 17, while the current from rail 9 flows through the right hand half of the coil 11 to conductor 17. As the direction of the flow of these two currents is opposite, no 15 magnetization of the core 10 of bond E will take place. The currents which have joined in the conductor 17 are delivered to the center of the coil 13 on bond transformer F, divide and flow through opposite halves of 20 the coil 13, respectively to the rails 8 and 9 of the next section, for instance X, and as they flow in opposite directions do not magnetize the core 12. The coils 11, 13, therefore do not offer any considerable resistance 25 to the power current (whether it be a direct or alternating current) flowing to the generator through the traffic rails 8 and 9. It will be observed, however, that the coils 11 and 13 are connected across the rails 8, 9; 30 consequently, the current due to the difference of potential excited between the rails 8, 9, by the coil 13 acting as secondary of the bond transformer F and tending to flow through the whole of coil 11 of bond E in 35 one direction, is met by the reactance effect of the whole of coil 11, which practically resists the flow of such current and thereby tends to maintain the potential of the signaling current across the rails 8, 9.

40 The conductor 17, it will be observed, at the left hand end of the block X, is connected in Figs. 1 and 4, to the generators A, B, in Fig. 2, to the generator A and one terminal of the coil 16 of the transformer C, in 45 Fig. 3, to the generator A. The conductor 17, it will be observed, also forms a common return for both the power and the signaling current employed in all of the figures.

Instead of using a bond E and transformer F, as shown in Figs. 1, 2, 3, I may 50 use two bonds of similar construction, as shown in Fig. 4, and excite the difference of potential across the rails 8, 9, by means of an independent transformer G, having its 55 primary 18 connected across the conductors 15 and 17, and its secondary 19 across the traffic rails 8 and 9.

Referring now to the relay device, the relay device may have its field coil 20, connected directly across the source of signaling current, as shown in Figs. 2, 3 and 4, or across the terminals of the secondary coil 21 60 of a transformer I, as shown in Fig. 1, the primary 22 of which is connected across the 65 conductor 15 and a conductor 23; one ter-

70 minal of the primary is also connected to the conductor 17. Located in the field coil 20 of the relay H, is a device J, Fig. 1, through which an inductive resistance may be interposed in the field circuit of the relay.

K indicates the armature of the relay, which consists of a coil of wire 24, whose plane in its normal condition is parallel with the field of force between the pole pieces of the relay. The terminals of this 75 coil are connected across the rails 8, 9. Carried by this armature is an arm 25.

26 indicates a local circuit, in which is a solenoid core 27. One end of the local circuit is fastened to the arm 25 and the other 80 end to a contact plate 28.

29 indicates an armature located in the solenoid 27, and connected to the short arm of the semaphore 30.

In certain localities, as for instance, upon 85 elevated roads, it is useful to decrease the resistance of the return path for the power current, and for this purpose I provide the additional connecting feeder bonds L, which are constructed in all respects like the bonds 90 E and each of which has its coil 31 connected across the rails 8, 9, and also at its central point through a conductor 32 to the conductor 23, which conductor may, for instance, be the structure of an elevated road, 95 or other good conducting path.

The operation of my improved system is as follows:—The signaling current derived from the generator B, or from one phase of the generator A, but segregated from the 100 power current, Fig. 3, excites through the transformer bonds F, Figs. 1, 2, 3, or supplemental transformer G, Fig. 4, a difference of potential between the rail 8, 9. It will be seen that the power current, 105 which may be direct or alternating, flows along the traffic rails at the same time as the signaling current, there being no interference between the two currents. The signaling current also excites the field coil 20, of 110 the relay H, either directly as shown in Figs. 2, 3, 4, or through the instrumentality of a transformer I, as shown in Fig. 1. The voltage across the rails 8, 9, excites a current in the coil 24. Remembering now that the 115 signaling current exciting the field coil 20 of the relay H corresponds in phase with the current exciting the coil 24, of the armature K, a turning movement of the armature K will take place, which turning movement will cause the arm 25 to make contact with the plate 28 and close the local circuit 120

26, thereby causing the solenoid 27 to attract its armature 29 and carry the signal to the clear position, *i. e.*, the position shown 125 in blocks X and Z. The semaphore arm will be maintained in this position so long as a voltage exists across the rails 8, 9. Should this voltage be destroyed by any means, as for instance, by malicious inter- 130

ference or otherwise, the semaphore arm will automatically go to danger. Or, in the normal operation of the road, a car entering a block, in which case the wheels of the car and axles will short circuit the armature K of the relay. Or, in other words, prevent the current due to the difference of potential between the rails 8, 9 from flowing through said armature, with the result that the armature will return to its normal position and open the local circuit, thereby allowing the semaphore arm to drop by gravity to the danger position.

In the various diagrams I have shown the rails included in the primary circuit of the transformers. Manifestly, and to insure greater safety, I may excite the transformers which create a difference of potential across the rails by means of entirely independent conductors.

I wish it understood that I do not limit myself to the particular arrangement of circuits indicated in the accompanying diagrams, as it will be obvious to electricians, that many changes may be made without in any wise departing from the intent of my invention. Nor do I limit myself to the particular construction of bond or bond transformer, or relay, shown, as many changes may be made therein without involving any radical change in the operation of the system.

What I wish to have understood is—that I claim to be the first to have described and illustrated a system of automatic block signaling for electric railways where the conductivity of the traffic rails is practically the same, and will be maintained the same as in an ordinary electric railway, and which conductivity is not effected by having impressed thereon in the direction of the flow of the

power current or across the rails, an alternating current for signaling purposes.

Having thus described my invention, I claim:—

1. In a system of automatic block signaling for electric railways, a trackway having both rails divided into block sections, signaling devices for each block, an alternating current generator for supplying alternating currents for said signaling devices and also supplying the power currents for the operation of electric cars of the railway independent of the signaling devices controlled thereby, coils bridging the rails of each section at each end thereof and a conductor between the middle points of adjacent coils through which the power currents pass unimpeded by reactance, and transformers receiving currents from said generator and supplying said signaling devices.

2. In a system of automatic block signaling for electric railways, the combination with the usual contact conductor or third rail, of an alternating current generator adapted to generate a plurality of phases and having one terminal of one phase connected to the contact conductor or third rail, a coil joining the ends of the traffic rails, the other terminal of said phase being connected to the central point of said coil, signaling devices for each block, and a transformer connected to another phase of said alternator and its secondary supplying current to the signaling devices.

In testimony whereof, I affix my signature, in the presence of two witnesses.

FITZHUGH TOWNSEND
